UNITED STATES PATENT OFFICE.

OSCAR L. SMITH, OF PHILADELPHIA, PENNSYLVANIA.

FIBER-SHIPPING-CASE-SEALING MACHINE.

Application filed November 17, 1919. Serial No. 338,659.

To all whom it may concern:

Be it known that I, OSCAR L. SMITH, a citizen of the United States, and a resident of Philadelphia, in the county of Philadelphia and State of Pennsylvania, have invented an Improvement in Fiber-Shipping-Case-Sealing Machines, of which the following description, in connection with the accompanying drawings, is a specification, like characters on the drawings representing like parts.

This invention relates to machines for sealing fiber or pasteboard shipping cases and more particularly to mechanism for securing the overlapping flap members of the casing by metallic fastenings.

In view of the cost of boxes or cases formed of wood or like material, and the time necessary in the construction of such form of cases, it has become more and more desirable to employ fiber shipping cases which are of a knock-down character and usually formed of blanks which can be quickly assembled.

The use of these fibrous or pasteboard shipping cases has created a demand for a reliable metallic seal for joining the adjacent edges. The main difficulty in such metallic seal is encountered after the case has been filled and the adjacent edge portions of the flaps are to be connected together. An important feature of the present invention, therefore, consists of novel means for reliably supporting the adjacent edges of the flaps of a fiber shipping case and maintaining them in proper co-relation during the driving of metallic fasteners, such as rivets, or the like.

In carrying this feature of the invention into practical effect the adjacent edges of the flaps to be connected by the metallic fasteners are guided and supported by a rigid member containing an anvil over which the flaps of the fiber shipping case are moved during the driving of the fasteners. More specifically considered, the guide for the adjacent edges of the flaps comprises a rigid goose-neck between the overlapping members of which one of the edges passes while the other edge is supported by an exterior portion of the goose-neck. Preferably the fiber sealing case is supported on a table or suitable rest and is moved thereon relative to the goose-neck

and the fastener-inserting mechanism during the sealing operation. In the illustrated form of the invention the fasteners are shown as rivets which pass through the overlapping adjacent edges of the fiber seal flaps and are clinched on the under-side of the underlapping flap, but certain features of the invention are applicable to other forms of metallic sealing machines.

In the drawings:

Fig. 1 is a perspective view showing a rivet driving machine equipped with the present invention;

Fig. 2 is an enlarged detached detail showing the form of guide or goose-neck, the view being taken at the front and delivery side thereof;

Fig. 3 is a perspective view looking from the left and front of the machine;

Fig. 4 is an enlarged detail front elevation showing more particularly the guide or goose-neck and the cooperating rivet driving means;

Fig. 5 is a side elevation looking from the left of Fig. 3 and showing the rivet driven through the overlapping edges of adjacent flaps and clinched;

Fig. 6 is a sectional detail showing the manner of supporting the goose-neck hanger.

The rivet driving machine may be of any usual or desired character and in the present invention comprises a base portion 1 from which rises the column 2 surmounted by the arm 3 which supports certain of the operating parts.

A hopper 4 is mounted upon the arm 3 and a chute 5 leading therefrom delivers the fastenings to the driving mechanism. The driving mechanism may be variously contrived, but in the present instance comprises the lever or driving arm 6 pivoted at 7 to lugs 8 rising from the arm 3. The lever 6 may be actuated under manual control. Mounted on a bracket 9 extending from the arm 3 is the shaft 10 carrying the belt pulley 11 which may be driven from any suitable source of power such, for instance, as the lineshaft. Connected to the lever 6 is a link 12 which may be actuated at desired intervals by suitable means driven from the driving shaft 10 under control of the treadle 13. The treadle 13 is pivoted to the machine frame at 14 and has an arm

15 pivotally connected at 16 to a link 17 for controlling the operative or inoperative relation of the link 12 and its actuating means. The parts heretofore described may be of 5 usual and well understood character, and as they form no essential part of the present invention so far as details are concerned, further description thereof appears unnecessary.

10 A spring 18 connected to the treadle arm 15 serves normally to depress the rod 17 and lift the treadle 13, the construction being such that upon depression of the treadle 13 the rod 17 is raised to throw into operation 15 the driving mechanism.

The lever 6 is connected at 19, Fig. 3, to the driver 20 which is guided in the head 21. Slidably mounted in the head 21 adjacent the driver is the slide 22, the lower 20 end of which carries the nose 23 into which the rivets are delivered one by one by a suitable separating device, common in this class of machines. The slide 22 is normally held raised by a spring 24 one end of which 25 is connected to a pin 25 extending from the slide and at the other end to a pin 26 extending from the head 21, the construction being such that when the driver 20 is raised or inoperative, the spring 24 lifts 30 the nose 23 into position adjacent to the chute 5 for receiving a staple. The machine thus far described contains nothing essentially new and is conveniently illustrated herein as showing one good form of means 35 for driving rivets. Mounted on and secured to the arm 3 is a hanger 27 preferably provided with shoulders 28 which engage flanges formed in the overhanging portion of the arm 3. One or more bolts 29, Figs. 3 40 and 6, serve to maintain the hanger 27 in rigid connection with the arm 3.

The hanger 27 has secured to it the guide or goose-neck by which the adjacent and overlapping edges of the flanges to be sealed 45 are supported and guided. In the present instance the hanger 27 is provided with a recessed portion 30, Fig. 5, in which is received a correspondingly shaped lug 31 extending rearwardly from the goose-neck 32, 50 and a bolt 33 rigidly secures the goose-neck 32 to the hanger.

The guide or goose-neck 32 extends downwardly and frontwardly, as indicated in Fig. 2, the downward and frontwardly extending 55 portions thereof, as at 34, being preferably inclined towards the front edge portion of the hanger at 35 where the hanger turns to form the lower member 36 of the goose-neck. In order that the nose 23 and 60 the driver may descend and carry the adjacent superposed edges of the overlapping flaps into substantial contact, the goose-neck is recessed or cut away as at 37, and the lower member 36 of the goose-neck, adjacent 65 the cut away portion, carries an anvil 38,

preferably formed as a removable steel block to resist the downward thrust of the driver and effect a clinch of the rivet.

As best indicated in Figs. 2, 3 and 4, the upper supporting surface 34 of the goose-neck inclines from the left or entrance of the work, towards the riveting point at the right or delivery end of the goose-neck, and both portions 34 and 36 of the goose-neck provide unyielding and rigid guides or supports for the adjacent edges of the overlapping flaps. This is well indicated in Fig. 4, wherein the upper flap *a* of the fiber shipping case, is shown resting upon the upper surface 34 of the goose-neck, while the lower 80 or underlying flap *b* of the fiber shipping case enters the recess 39 between the upper surface of the lower member 36 and the lower surface of the upper member or portion 34 of the goose-neck. By reason of the incline 85 of the supporting surface 34 of the goose-neck, the upper overlying flap *a* is directed downwardly towards the lower or underlying flap as the two flaps approach the riveting point, as indicated in Fig. 4, the construction being such that when a rivet is driven, as indicated by dotted lines in Fig. 4, and full lines in Fig. 5, the overlying flap is bent downwardly towards and into contact with the lower flap. 95

When a fiber shipping case is to be sealed by rivets in accordance with the present invention, the leading edges *c* of the overlapping flaps of the shipping case *d*, are introduced to the guide or goose-neck by passing the lower sealing flap edge into the space 39 of the goose-neck so that the lower member 36 of the goose-neck travels inside of the shipping case above the contents thereof, and the overlapping flap *a* is introduced above and upon the surface 34. The treadle is then depressed and a rivet *e* driven, its ends being clinched by the anvil 38, as indicated in Figs. 4 and 5. The shipping case is then advanced a desired distance and another rivet driven, and so on throughout the entire length of the overlapping edges to be united. 105

It is convenient to support the shipping case during the sealing operation upon a table or support, and in the present instance the table 40 is mounted upon a sleeve 41 into which projects the threaded post 42 mounted adjustably in the machine frame at 43. The sleeve 41 preferably carries a lug 115 or key 44 which travels in a suitable slot or guide 45 on the threaded post 42, the construction being such that as the table is raised and lowered, it will maintain its position without rotation. Loosely mounted on the sleeve 41 is a threaded adjusting collar 46 adapted to engage the threaded post 42, the construction being such that by rotation of the collar 46 the sleeve 41 and, perchance the table 40, may be raised or lowered into con- 120 125 130

venient position as dictated by the size of the shipping case to be sealed. The threaded post 42 may be held adjustably to the machine frame by a set screw 47, or other convenient means.

From the construction described it will be apparent that when the upper and lower adjacent edges of overlapping flaps of the sealing case are associated with the goose-neck, as hereinbefore described, the sealing case may be moved upon the table 41 progressively after each drive of a rivet, the lower rigid member 36 and the anvil 38 at such times traveling on the inside of the shipping case below the lower flap *b*.

The present invention has been described more particularly with reference to a suitable driving machine because in practice it has been found that staples driven through overlapping flaps and clinched by the anvil afford a suitable permanent and secure metallic fastening for the adjacent edges of the overlapping flaps, but it is to be understood, of course, that other forms of fastenings may be driven without departing from the true scope of the present invention as pointed out in the claims.

From the described embodiment of the invention it will be understood that the goose-neck guide or flap support is secured adjacent the fastening inserting mechanism and that a part extends downwardly and transversely of and under one of the sealing flaps and that another part, which constitutes the anvil support, extends transversely in the opposite direction beneath the other flap and within the shipping case, so that as the shipping case is fed past the fastening inserting mechanism the two transversely extending portions enter the case from above and pass between or separate the two flaps to be sealed. The anvil being rigid and rigidly held from the machine frame presents a reliable clinching means for the rivets as the shipping case is moved past the goose-neck.

Claims:

1. A machine for sealing the overlapping flaps of a fibrous shipping case after the contents of the case have been placed therein, comprising, in combination, a metallic fastening inserting mechanism, an anvil adapted to engage and support the inner face of the underlapping flap during the sealing thereof and to clinch the fasteners inserted by said mechanism, a rigid, reversely-bent goose neck having a portion extending between the adjacent edges of said overlapping flaps and another portion rigid with the first portion and extending beneath the lower face of the underlapping flap to support the anvil, and means for rigidly supporting the goose neck from a position above the case being sealed.

2. A machine for sealing the overlapping flaps of a fibrous shipping case while the

contents of the case remain therein, comprising, in combination, a metallic fastening inserting mechanism, and anvil extending within the case for supporting adjacent edge portions of the flaps to be sealed, a rigid anvil supporting arm that extends transversely under the overlapping flap, and has an oppositely extending portion that projects under the underlapping flap within the case to rigidly support the anvil in engagement with the lower face of the underlapping flap, and means for rigidly supporting said arm and its anvil from a position above the case being sealed.

3. A machine for sealing the overlapping flaps of a fibrous shipping case while the contents of the case remain therein, comprising, in combination, a driver for driving metallic fastenings, a rigid arm that extends transversely of and under the inner face of one of the overlapping flaps, an anvil support that extends from the arm transversely in an opposite direction beneath the underlapping flap, and an anvil rigidly supported by the anvil support, means for rigidly supporting said arm and anvil from a position above the case being sealed, and means for actuating the driver to drive metallic fastenings through the adjacent edges of the overlapping flaps as they are fed over the anvil.

4. A machine for sealing the overlapping flaps of a fibrous shipping case while the contents of the case remain therein, comprising, in combination, a metallic fastening inserting mechanism, a rigid guide having a portion extending between the adjacent edges of the overlapping flaps to be sealed, and another portion extending below the edge of the underlapping flap within the interior of the shipping case and having an anvil for supporting the flaps while the metallic fastening is inserted, and means having the guide rigidly secured thereto and serving to rigidly support the portion of the guide within the case.

5. A machine for sealing the overlapping flaps of a fibrous shipping case while the contents of the case remain therein, comprising, in combination, a support, a metallic fastening inserting mechanism carried by the support, a guide depending rigidly from said support and having two supporting and guiding portions, one of which extends between the overlapping portions of the flaps and the other of which passes around the edge of the underlapping flap and extends into the shipping case under the underlapping flap, and an anvil supported by the last mentioned guiding portion below and in supporting engagement with the underlapping flap, said depending guide adapted to form the sole support for the anvil while the metallic fastening is inserted.

6. In combination with a fastener inserting mechanism, a clincher block for insertion

beneath one of the overlapping cover portions on a fiber shipping container, and a support for the clincher block extending upwardly and over between the overlapping portions whereby the block may be moved along beneath the flange so as to clinch the fasteners which fasten the two flaps along their overlapping portions, said

support being of dimensions and construction to be capable of clinching the fasteners 10 without any additional support beneath the clincher block.

In testimony whereof I have signed my name to this specification.

OSCAR L. SMITH.
